(57) **CLAIM**

The ornamental design for a watch band storage case, as shown and described.

DESCRIPTION

FIG. 1 is a front perspective view of a first part of the watch band storage case showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of a second part of a first part of the watch band storage case showing my new design;

FIG. 10 is a rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a perspective view of the first part integrated with the second part of the watch band storage case; and,

FIG. 18 is a perspective view when the watch band storage case is closed.

The broken lines shown in the drawings are included for the purpose of illustrating portions of the watch band storage case that form no part of the claimed design.

1 Claim, 18 Drawing Sheets
